US00D456776S

(12) **United States Design Patent** (10) Patent No.: **US D456,776 S**
(45) Date of Patent: ** May 7, 2002

(54) **SNAP SENSOR CONNECTOR**

(75) Inventor: **Eric Lindekugel**, Fort Collins, CO (US)

(73) Assignee: **Datex - Ohmeda, Inc.**, Madison, WI (US)

(**) Term: **14 Years**

(21) Appl. No.: **29/136,021**

(22) Filed: **Jan. 23, 2001**

(51) LOC (7) Cl. **13-03**

(52) U.S. Cl. **D13/146; D24/169**

(58) Field of Search **D13/146; D24/169; 439/599, 589, 374, 909, 352, 357, 465, 687, 696, 731, 906; 600/322, 323**
